LASTING MACHINE

Joseph Fessa, Salem, Mass., assignor to United
Shoe Machinery Corporation, Flemington, N. J.,
a corporation of New Jersey

Application October 26, 1944, Serial No. 560,382

25 Claims. (Cl. 12—1)

1

This invention relates to shoe machines and particularly to machines for lasting the uppers of shoes or performing analogous operations on other shoe parts.

In lasting, as this term is understood in the trade, the upper stock is tensioned heightwise of the last, its lasting margin is drawn over, or otherwise worked into overlasted position, onto the bottom of the shoe, and the overlasted margin is secured in lasted position, as by cement or metallic fastenings, to a shoe-bottom member such, for example, as an insole. Recently there has been introduced to the trade a type of shoe sometimes called a slip-in lasted shoe, the manufacture of which, while it does not involve the conventional lasting operation, as outlined above, does employ a procedure closely analogous thereto, namely, the operation of tensioning a platform cover heightwise of the shoe, working the margin of the cover stock over onto a platform which serves as a shoe bottom member, and securing, as by cement, this overdrawn margin to the platform.

It is an object of this invention to provide a novel and improved machine for performing either the conventional lasting operation, or such an analogous operation as the one just mentioned. Accordingly, in this specification, as well as in the claims, the term "lasting" is used in a somewhat broadened sense and is intended to include not only the conventional lasting operation but also other analogous operations, while the terms "lasting margin" and "overlasted margin" are intended to include that portion of a platform cover, or other part, which corresponds to the like portion of the upper stock of a conventional shoe.

More particularly, it is an object of this invention to provide an improved lasting machine that is very speedy in operation, efficient in its action, and especially adapted for performing lasting operations in which the securing of the overlasted margin of the stock to the bottom of the shoe is effected by means of an adhesive, and where the lasting operation proceeds step by step without interruption along the peripheral edge of the shoe bottom. It is, however, to be understood that in certain aspects the invention is of broader scope and that features thereof have utility in other types of lasting.

It is also an object of this invention to provide an improved lasting machine in the operation of which the lasting operation progresses automatically along the peripheral edge of the shoe bottom by small, but finite, increments, and

2

which affords protection against displacement of the lasted stock or distortion of the shoe-bottom part during the lasting operation.

With these and other objects in view, the herein illustrated machine is, in accordance with features of the invention, provided with a rapidly reciprocating gripper for seizing the lasting margin of the stock to be lasted, in different locations successively along the edge of the shoe bottom, and for tensioning it heightwise of the shoe by pulling it inwardly from the edge of the shoe bottom in a direction substantially parallel to the shoe bottom and over a protective shield portion of a shoe bottom rest; a presser-feed member, operating in time relation to the gripper, for pressing and pounding the overdrawn lasting margin of the stock into adhering relation with the shoe-bottom part and also movable, thereafter, in a direction to feed the shoe; and a feed-retaining member for preventing retrograde movement of the shoe and for retaining previously overlasted stock from being displaced by the next succeeding action of the gripper.

For preventing the adhesively coated lasting margin of the stock from sticking to the gripper jaw which engages it, the machine, in accordance with a further feature of the invention, is provided with gripper-operating means arranged to effect separation of the gripper jaws by individual movements thereof in opposite directions away from the said margin. In the illustrated machine the gripper mechanism comprises a power-reciprocated rear gripper jaw, a front jaw associated therewith for movement relative thereto, resilient means for closing the jaws, and means controlling the position of the front jaw so that the jaws close on the stock, move together forwardly over the shoe bottom, and finally separate to release the stock, the controlling means being arranged to continue the forward movement of the front jaw, as the rear jaw moves rearwardly, thus to effect separation of the jaws in the manner set forth.

As stated above, the stock is tensioned over the protective shield portion of a bottom rest, and to facilitate the introduction of work to the machine this bottom rest is, in accordance with a feature of the invention, movable by spring means to an inoperative position, operator-controlled means being provided for returning the bottom rest to operative position, against the action of the spring means, in which its shield portion will engage the bottom of a shoe held thereagainst, by the operator, close to its marginal edge. This spring means is also adapted to hold the front

gripper jaw in its forward position and away from the reciprocating rear jaw, thus further facilitating the insertion of the lasting margin of the stock between the jaws.

The presser-feed member of the illustrated machine, as above mentioned, acts as a presser, or hammer, to press, or pound, the overlasted margin of the stock into adhering relation to the bottom of the shoe, and also as a feed-foot to move the shoe bodily in a feeding direction. To facilitate this feeding action this presser-feed-foot is, in accordance with another feature of the invention, constructed and arranged to move the shoe downwardly and away from the bottom rest, thus avoiding any tendency for the adhesively coated shoe bottom to stick to the bottom rest or to drag thereon. This presser-feed-foot descends substantially vertically onto the overlasted margin close to the point of action of the gripper, and its feeding increment is so small that any fullness of the stock between the successive points of action of the presser-feed-foot is nicely folded into small and unobjectionable plaits, a feature of especial importance where the lasting operation proceeds around sharply curved portions of a shoe, as at the toe and heel ends, and adjacent to the ball. The effectiveness of the presser-feet-foot to effect adherence of the stock, and to feed the shoe, and that of the feed-retainer to prevent retrograde movement of the shoe, is enhanced by confining their zones of operations to narrow areas and by providing them with sharpened teeth.

These and other features of the invention will become apparent in the following detailed description of the embodiment thereof shown in the accompanying drawings and will be pointed out in the claims.

In the drawings,

Fig. 1 is a view in side elevation of a machine embodying the features of the present invention, certain portions being broken away to show the interior construction;

Fig. 1a is a detail view of one of the operating elements of the machine;

Fig. 2 is a plan view of the machine shown in Fig. 1, the top portion of the head being removed to show the mechanism contained therein;

Fig. 3 is a view in front elevation of a part of the machine shown in Fig. 1 and showing the operating instrumentalities;

Fig. 4 is a view in side elevation of the operating instrumentalities shown in Fig. 3;

Figs. 5 and 6 are front and side elevation views, respectively, of the operating instrumentalities shown in Fig. 4 but with these instrumentalities in different operating positions;

Fig. 7 is a view in side elevation of the front part of the machine with the operating instrumentalities in position to receive a shoe and with certain parts omitted; and

Fig. 8 is a Timing Chart.

Referring to the drawings, the operating instrumentalities of the illustrated machine comprise a gripper, including a rear gripper jaw 10 and a front gripper jaw 12, for seizing the lasting margin of the stock and applying lasting stress thereto; a shoe bottom rest and lasting shield 14 for engaging and positioning heightwise, the bottom of a shoe and over which the lasting margin is drawn by the stress applied thereto by the gripper; a presser-feed member 16 for pressing the tensioned lasting margin down onto the bottom of the shoe and for exerting a feeding force on the shoe; a feed-retaining member 18 for holding the shoe against retrograde movement

during the return, or back-feeding, movement of the presser-feed-foot; and an edge gage roll 20 for positioning the shoe laterally. These instrumentalities are all mounted on, and operated by mechanism contained within, a hollow head construction 22 comprising a lower portion 24 and a removable top part 26 secured thereto by means of cap screws 28, 28.

The rear gripper jaw 10 is attached, by means of a clamping bolt 30, to the forward end of a carrier 32 which is supported by two rocker arms 34, 36 journaled respectively on fixed cross shafts 38 and 40 that extend across the lower portion 24 of the head 22. This carrier is pivotally secured to these rocker arms by means of studs 42, 44 and is movable forwardly and rearwardly of the machine by means of a third rocker arm 46 that extends upwardly from a hub member 48 common to it and to the rocker arm 36. The rocker arms 34 and 36, together with that part of the carrier 32 which extends between said arms, constitute a parallel motion linkage so that the carrier always remains horizontal during its forward and rearward movements.

For oscillating the rocker arm 46, to impart the aforementioned movements to the carrier 32, there is provided an eccentric 50 formed integrally with a main drive shaft 52 that extends across the lower portion 24 of the head and which is journaled in anti-friction bearings 54, 56 mounted in said lower head portion. An end of this shaft projects beyond one side of the head, see Fig. 2, and on this end there is secured a drive pulley 58 which is connected by means of a belt, not shown, to any suitable source of power such as, for example, an electric motor. Surrounding the eccentric 50 there is an eccentric strap 60 from which extends an arm 62. This arm is connected by means of a ball joint, including a ball 64, to a link 66 and by a ball joint, including a ball 68, to a link 70, a spring clip 72 serving to hold the links 66 and 70 and the arm 62 in assembled position on the balls 64 and 68. The link 70 is connected by a ball joint, comprising a ball 71 and a spring clip 73, to the upper end of one arm 74 of a bell crank having a second arm 76, located on the outside of the head portion 24 and provided with an operating handle 80 in which is positioned a spring-locking plunger 82. This locking plunger is adapted to be positioned selectively in one of several recesses 84, formed in an arcuately shaped raised portion 86 on the head, see Fig. 2, thus to vary the length of the toggle formed by the link 70 and the arm 74 for a purpose to be explained below. The link 66 is connected to the rocker arm 46 by means of a ball joint including a ball 88 and a spring clip 90. As the main shaft 52 and eccentric 50 are rotated the link 70 will be oscillated about the ball joint 71 and this oscillating movement of the link 70 will be transmitted to the arm 46 by the link 66, thus causing the carrier 32, together with the inner gripper jaw 10 which is attached thereto, to be reciprocated forwardly and rearwardly of the machine. By varying the length of the toggle formed by the link 70 and the arm 74, in the manner pointed out above, the extent of the forward movement of the carrier and of the rear gripper jaw 10 may be varied.

The front gripper jaw 12 is secured, by means of a clamp nut 100 and washer 101, on the outer end of an elongated rod 102 which is slidably mounted in bearing bores 104, 106 formed in bosses 108, 110 on the carrier 32. The jaw 12

fits into a hole 105 formed in an enlarged portion 107 of the rod 102 which, beyond this enlarged portion, is reduced in diameter to receive the washer 101 and threaded for the clamp nut 100. At its back end this rod abuts a second rod 103 which is connected, by means of a ball joint comprising a ball 112 and a spring clip 114, to the top end of a cam lever 116 which is pivotally mounted, between its opposite ends, on a stud 118 that is carried in a boss 120 formed integrally on the upper side of a centrally located and longitudinally extending web portion 122 of the lower head portion 24. The rod 103 is held in alignment with rod 102 by means of a guide bore 105 formed in an upstanding flange member 107 that is secured to the top of the web portion 122 by screws 109. The lower end of the cam lever 116 is provided with a cam surface 123 comprising an arcuate part 124 and an angular, or eccentric, part 126. This lever is continuously urged to swing in a clockwise direction to move the rod 103 rearwardly, to the right, Fig. 1, by means of a coil spring 128, connected between an eye 133 in the lever and a post 132 mounted on the head portion 24, to a position determined by the engagement of a part of the cam surface 123 with a roller 134 carried on the outer end of a lever 136 which has a hub 137 journaled on a shaft 138 supported in ears 140, 142 on the head portion 24. The lever 136 is oscillated, to present the roll 134 to the different parts 124 and 126 of the cam surface 123 on lever 116, by means of the eccentric 50 which carries a second strap 144 having an arm 146 that is connected to the lever 136 by means of a ball joint comprising a ball 147 and a spring clip 148.

The rod 102 is urged rearwardly of the machine by means of a coil spring 150 that extends between the upper end of the front gripper jaw 12 and an arm 152 secured to a shaft 154 that is journaled in the top part 26 of the head. Also secured to the shaft 154, on the outside of the upper head part 26, is an arm 156 having a spring-locking plunger 158 which is adapted to be positioned in one of several recesses 160 formed in an arcuate boss 162 thus to vary the tension of the spring 150. In the position of the parts as shown in Fig. 1, the rear gripper jaw 10 is in its extreme rearmost position while the front gripper jaw 12 is held in its extreme forward position, against the action of spring 150, by the engagement of roll 134 on the arcuate part 124 of the cam surface 123. Now as the main drive shaft 52 is rotated, in the direction of the arrow, Fig. 1, the carrier 32, together with the rear gripper jaw 10, will be moved forwardly of the machine, to the left as viewed in Fig. 1, by the eccentric 50 acting through arm 62, link 68 and rocker arm 46. At the same time lever 136 will be swung in a clockwise direction, eccentric 50 and arm 146, thus moving the roll 134 up over the angular, or eccentric, part 126 of the cam 123 and permitting spring 128 to swing lever 116 in a clockwise direction, and to move rod 103 to the right, and spring 150 to move the rod 102, together with the front gripper jaw 12, rearwardly of the machine, to the right, Fig. 1. These movements of the two gripper jaws continue during a quarter turn of the shaft 52 and until the rear and front jaws meet, whereupon the front jaw 12 will then be moved forwardly, to the left, Fig. 1, against the action of spring 150, by the continued forward movement of the carrier 32 and rear jaw 10, for the next quarter turn of the main drive shaft 52. This half turn of the eccentric 50 will have returned

the lever 136 and its roll 134 to the position shown in Fig. 1 where it will again engage the arcuate part 124 of the cam 123 and now so position rod 103 as to prevent rearward movement of the front gripper jaw as the carrier 32 and the rear jaw are returned to their positions as shown in Fig. 1 during the next half turn of the shaft 52 which completes the cycle. During this last half turn the roller 134 travels on the arcuate surface 124 of the cam 123, which has its center about the axis of the shaft 138. The cam surface 126 is so shaped that the gripper jaws will come together, to close on the lasting margin of the upper of a shoe being lasted, just a slight distance inwardly from the edge of the shoe when it is being held against the edge gage roll 20, and as the rear jaw forces the front jaw forwardly of the machine the upper stock thus gripped firmly between the jaws, under the action of the spring 150, will be drawn inwardly over the bottom of the shoe. Also, as the front jaw is picked up by the rear jaw, the rods 102 and 103 will separate slightly, thus avoiding any chance of the rod 103 pushing rod 102 to the left and relaxing the grip of the jaws 10 and 12 on the stock. Preferably, and as shown, the cam part 124 is so constructed that the arm 116 is given a slight additional angular movement in a counterclockwise direction just as the rear gripper jaw starts its rearward movement and enough to move the front gripper jaw away from the stock which has just been pulled. This additional forward movement of the gripper jaw 12 assures that the adhesive coated stock will not stick to the jaw.

As the stock is thus pulled inwardly over, and in a direction substantially parallel to, the bottom of the shoe, it is drawn over the inner end of the bottom rest 14, and also over in contact with a portion 170 thereof which is positioned directly below and in alignment with the line of action of the gripper so as to constitute a lasting shield or abutment. Thus the horizontally directed stress applied by the gripper is transposed into a vertical pull for tensioning the stock in a direction perpendicular to the shoe bottom and, at the same time, distortion of the shoe bottom member prevented. The bottom rest and lasting shield 14 is mounted for movement outwardly away from the edge gage roll 20, for the purpose of facilitating the beginning of a lasting operation, in the following manner. The bottom rest and lasting shield 14 is secured by means of bolts 172 to an arm 174 which extends downwardly from a hub member 176 that is journaled on a shaft 178 supported in a forwardly projecting part of the upper head portion 26. Also extending from this same hub member is an arm 180 having a bifurcated end 182 embracing a sliding block 184 in which is journaled an eccentric portion 186 of a shaft 188 that is also journaled in the head portion 26, Figs. 1, 3 and 7. The shaft 188 extends beyond one side of the head portion 26, see Fig. 3, and on this projecting end of the shaft there is secured a pinion 190 which meshes with a gear quadrant 192 having a hub 194 that is journaled on the shaft 154 which, as pointed out above, extends across the top part of the upper head portion 26. Also extending from the hub 194 are two other arms 196 and 200. The arm 196 is connected by means of a rod 202 to a treadle, not shown, while extending between the arm 200 and a pin 204, mounted in the head portion 26, is a tension spring 206 which tends to hold the arm 200 against a stop pin 208 with the bottom rest and lasting shield 14 moved outwardly and to

the left from the position shown in Fig. 1, when the treadle is released, to the position shown in Fig. 7. Depression of the treadle, however, swings the arm 200 in a clockwise direction and to the position shown in Fig. 1, against a stop pin 210, thus moving the bottom rest and lasting shield 14 into the operative position shown in this figure.

Also extending from the hub 176 is an arm 212 which is connected by means of a link 214 to an arm 216 which extends downwardly from a hub 218 which, like hub 194, is freely rotatable upon the shaft 154. This arm has at its lower end an offset boss 220 which, when the treadle is released, bears against a collar 222 on the rod 162 thus to hold the front gripper jaw 12 in its forward position. Accordingly, until the treadle is depressed and the bottom rest and lasting shield 14 moved into operative position, the rear gripper jaw 10 merely reciprocates idly without engaging the front gripper jaw or exerting any pulling action on the stock. As will be seen from Fig. 7, when the outer jaw is thus held in its outermost position by the boss 220 the rods 162 and 163 are separated a small amount.

The stock which has been tensioned and drawn inwardly over the shoe bottom by the gripper in the manner above explained is pressed firmly against the bottom of the shoe, and into lasted position thereon, just as it is released by the gripper, by means of the presser-feed-member, or presser-feed-foot, 16, which thereafter, and while in engagement with the stock, is moved laterally to feed the shoe. This presser-feed-foot 16 is adjustably secured by a screw 240 to the outer end of a lever 242 which is pivotally mounted by means of a stud 241 on an upwardly extending arm 244 formed integrally with a shaft 246 that is journaled in an elongated bushing 248 mounted in a bore 250 in the web portion 122. The lever 242 is oscillated, in time relation to the operation of the grippers, to move the presser-feed-foot 16 against the stock, by means of an eccentric 252, carried by the shaft 52, and the shaft 246 is oscillated, to move the presser-feed-foot back and forth in a direction extending lengthwise of the shoe, by means of an angle crank 254 also carried by the shaft 52, see Fig. 1a. To augment its pressing action and to insure against slippage on the stock, the presser-feed-foot 16 is formed as a narrow blade-like element and is provided with a series of sharpened teeth 255, see Figs. 1, 4, 6 and 7.

Surrounding the eccentric 252 is a strap 256 from which extends an arm 258 which is connected, by means of a ball joint comprising a ball 260 and a spring clip 262, to an arm 264 that extends downwardly from a hub member 266 journaled on a shaft 268 mounted in a side wall of the housing portion 26, see Fig. 2. Also extending from the hub 266 is an arm 270 and connected to the outer end of this arm by a ball joint comprising a ball 272 and a spring clip 274 is a link 276 the opposite end of which is connected, by a ball joint comprising a ball 278 and a spring clip 280, to one end of the lever 242.

In the position of the parts as shown in Fig. 1, the presser-feed-foot 16 is in its lowermost position and has just completed a feed stroke. During the following half turn, which completes the cycle, the arm 270 will swing in a counterclockwise direction, considerably beyond the dead-center position shown, and so as to swing the lever 242 in a clockwise direction, Fig. 1, and thus elevate the presser-feed-foot 16 away from the work. The action of the angle crank 254 is so related to

that of the eccentric 252 that the shaft 246 is rotated in a direction to move the presser-feed-foot in a lengthwise direction and away from the lasting shield 14, to the left in Fig. 3, during the time that the presser-feed-foot is down against the work, and to return, or back feed, the presser-feed-foot, movement to the right in Fig. 3, while the presser-feed-foot is elevated away from the work. The presser-feed-foot 16 is preferably so arranged that in moving downwardly against the shoe it tends, momentarily, to push the shoe slightly away from the bottom rest 14, or at least appreciably to reduce the pressure of the shoe bottom against the bottom rest, thus reducing any tendency of the bottom rest to stick to the bottom of the shoe, see Figs. 3, 4, 5 and 6. The angle crank 254 operates in a block 253 that is embraced by an elongated yoke member 282, see Fig. 1a, which is secured to the shaft 246 by means of a set screw 284, see Fig. 2. The hub member 266 is held on the shaft 268 by means of an upstanding piece of flat stock 286 which is mounted on a reduced end of the shaft 40 and held against a boss 288 on the web portion 122 by means of a nut 290.

The shoe is held against retrograde movement during the return, or back-feeding, movement of the presser-feed-foot 16, and lifting of the stock by the next succeeding pulling action of the gripper is prevented, by the feed-retaining member 18. The member 18 is secured by means of a bolt 292 to the outer end of an arm 294 which is formed integrally with a hub 296, journaled on a shaft 298 mounted in the head portion 24. Also extending from the hub 296 are two other arms 300 and 302, the former of which extends upwardly to receive a tension spring 304, stretched between it and an anchor pin 306 carried by the upper head portion 26, see Fig. 1, while the latter arm extends downwardly and rearwardly and is formed with a cam track 308, having an arcuate part 307 and an eccentric part 309, over which travels a cam roller 310. The cam roller 310 is journaled on a stud 312 mounted in an arm 314 which extends radially from the hub member 266. The cam track 308 is so shaped that as the hub 296 is oscillated, by the eccentric 252, link 285 and arm 264, the feed-retaining member 18 will be successively urged toward the shoe bottom, by the spring 304, held in this position for a half turn of the main shaft and while roller 310 rides on the arcuate part 307, and raised therefrom by the roll 310 acting against the eccentric part 309 of cam surface 308. These movements of the feed-retaining member are so timed that it comes down against the overlasted stock just as the presser-feed-foot 16 completes a feeding movement, remains down on the stock, to prevent retrograde movement of the shoe and lifting of the overlasted stock by the gripper, while the presser-feed-foot is back feeding and during the next closing and pulling action of the gripper, and then is lifted away from the shoe bottom just as the presser-feed-foot 16 begins its next succeeding feeding movement. To augment its holding and pressing action the feed-retaining member is formed as a narrow blade-like element and is provided with a series of sharpened teeth 315 that are exactly similar to the teeth 225 on the presser-feed-foot 16.

The several operating elements which are contained within the hollow head construction 22 are lubricated by means of a splash feed system comprising a pair of paddles 430 which are secured to the hub 137 of the lever arm 136 and

which, as this hub is rapidly oscillated by the eccentric 50, dip into a body of oil contained within the lower head portion 24 and throw oil upwardly and forwardly within the closed head construction. To prevent any oil from passing out through an aperture 410, which is formed in a front cover plate 412, through which the several operating elements project, a baffle plate 414 is positioned as shown in Fig. 1 and secured to the top head part 26. The edge gage roll 28 is mounted on a stud 416 carried by a bracket 418 which is secured to the cover plate 412.

The individual functions of each of the several operating instrumentalities having been pointed out above, the manner in which these separate actions occur and how they are combined to tension the lasting margin of the upper of a shoe, or equivalent shoe part, such as, for example, the lasting margin of the platform cover C of a slip-in-lasted shoe, comprising an upper U and sock lining S mounted on a last L and having a platform P; draw it in over and press it down onto the bottom of the shoe; and effect an automatic feeding of the shoe, will now be explained. The shoe is presented to the machine while the treadle is released and with the bottom rest and lasting shield 14 in its inoperative position as shown in Fig. 7, the edge of the shoe being placed against the edge gage roll 28, the bottom of the shoe brought up against the lower face of the shield 14, and the lasting margin of the stock C introduced between the rear and front gripper jaws 10 and 12, the latter being readily accomplished, since at this time the front gripper jaw 12 is held in its forward position by the engagement of the boss 220 with the collar 222 on the rod 102 which carries this gripper jaw, and the shield 14 being out of the way. Depression of the treadle, not shown, will swing the bottom rest and lasting shield 14 into operative position, see Figs. 1, 3 and 6, and the arm 216 in a counterclockwise direction to move the boss 220 away from the collar 222, thus freeing the gripper jaw 12 for rearward movement by the spring 150 under the control of the rod 103 and cam tracks 124 and 126 on the lever 116, and rendering the gripper operative to take hold of the upper stock.

Referring to the timing chart, Fig. 8, and beginning at station 1 thereon, in which position 50 of the parts the presser-feed-foot 16, now in its lowermost position and against the shoe bottom, has just completed its feed stroke; the front gripper jaw 12 is in its forward position; the rear gripper jaw 10 is in its extreme rearward position; and the feed-retaining finger 18 is in its lowermost position, see Figs. 1, 3 and 4; a complete cycle of operations takes place in the following manner: During the first quarter turn of the main shaft 52, station 1 to station 2 on Timing Chart, the rear gripper jaw 10 moves forwardly and the front gripper jaw 12 moves rearwardly, these two gripper jaws eventually closing on the cover stock C adjacent to and just a short distance inwardly over the shoe bottom from the edge of the platform P; the presser-feed-foot 16 moves upwardly and away from the shoe as its return, or back-feeding, movement, to the right, Fig. 3, begins, while the feed-retaining member 18 remains down against the bottom of 70 the shoe. Now, and during the next quarter turn of the main shaft 52, station 2 to station 3, the gripper jaws 10 and 12 move forwardly together to draw the lasting margin C of the platform cover inwardly, from the edge of the plat-

form P, over in contact with the inner end 170 of the bottom rest and shield 14 to tension the cover heightwise and to draw it inwardly over the shoe bottom; the presser-feed-foot 16 completes its back-feeding movement and comes down on the tensioned and overdrawn cover stock adjacent to the gripper, see Figs. 5 and 6, and station 3 on the Timing Chart, Fig. 8. The gripper jaws 10 and 12 now start to separate, the rear jaw 10 being moved rearwardly by the eccentric 50 while the front jaw 12 is moved still further forward and is held in this forward position by the cam track 124 on the lever 116, the presser-feed-foot 16 is held down, to press the tensioned 15 and overdrawn upper stock C against the shoe bottom, and moved laterally, to the left, Fig. 5, to feed the shoe, so that at the end of the next quarter turn of the main shaft 52, station 4 of the Timing Chart is reached. At this time in the cycle, the gripper jaws have opened, presser-feed-foot 16 is down on the overlasted stock, and the feed-retaining member is still up and out of engagement with the overlasted stock. During the next and final quarter turn of the shaft 52, 20 which completes the cycle at station 1 on the Timing Chart, the rear gripper jaw 10 finishes its rearward movement while the front gripper jaw 12 is still held forward by cam part 124, the presser-feed-foot 16 completes its feeding stroke, and the feed-retaining member 18 moves downwardly toward the bottom of the shoe and into engagement with the overlasted margin of the stock C.

The bottom surface of the platform P adjacent to its marginal edge and the lasting margin of the cover C are both coated with a suitable adhesive so that the tensioned and overdrawn lasting margin of the cover C is caused to adhere to the shoe bottom by the pressure applied thereto by the presser-feed-foot 16. This pressure is, as will be observed from the Timing Chart, Fig. 8, maintained for a half turn of the shaft 52, station 3 to station 1, and is supplemented for the next half cycle, station 1 to station 3, by pressure applied at a closely adjacent point by the feed-retaining member 18. The pressure applied by the feed-retaining member also prevents stock which has been previously overdrawn and stuck down in lasted position by the pressure-feed-foot 16 from being lifted up or loosened by the rearward movement of the front gripper jaw or by the next tensioning or overdrawing action of the gripper. Due to the speed at which the machine is operated the presser-feed-foot 16 also has a hammer action since it strikes the overlasted upper a smart blow when it descends against it. This action facilitates the adherence of the overlasted stock, particularly when pressure-responsive cement is being used. By causing the gripper to draw the stock inwardly and over in contact with the inner end 170 of the bottom rest and shield 14 distortion of the edge of the relatively soft platform member P is avoided, while at the same time a strong heightwise pull, for tensioning the cover on the side of the platform P, is obtained. The slight additional forward movement of the front gripper jaw 12, effected by cam surface 124, separates this gripper jaw from the sticky inside surface of the cover and thus facilitates the lasting and feeding operations. The amount of pull applied to the stock, i. e., the strength of pull, may be readily varied in order to suit different types of materials and varying operating conditions, by changing the tension of the spring 150 in the manner explained above;

while the extent or duration of the pull may likewise be varied by manipulating the handle 39.

Preferably the machine is operated at a high speed, with the main shaft 52 driven at approximately 1200 R. P. M., so that about twenty complete lasting cycles are effected each second. A linear feeding increment of approximately one-eighth of an inch is obtained and this affords substantially $2\frac{1}{2}$ " per second movement of the shoe. Accordingly, an average size shoe can be lasted all around its entire periphery in a matter of only a few seconds. While the herein illustrated machine has been shown as operating on the lasting margin of a platform cover C, it will be readily understood that the machine will operate on the lasting margin of the upper of a conventional type shoe in the same speedy and efficient manner.

Having described the invention, what I claim as new and desire to secure by Letters Patent of the United States is:

1. A lasting machine having, in combination, means for engaging the bottom of a shoe adjacent to the marginal edge thereof, and means for seizing the lasting margin of the stock to be lasted and for pulling it over in contact with the shoe-bottom-engaging means and in a direction substantially parallel to the bottom of the shoe thereby to tension the stock in a direction normal to the bottom of the shoe and to draw the lasting margin inwardly over the shoe bottom.

2. A lasting machine having, in combination, a shoe-bottom rest having a shield portion adapted to be positioned on the shoe bottom and close to the marginal edge thereof, and gripper means for seizing the lasting margin of the stock to be lasted and for pulling it in a direction substantially parallel to the bottom of the shoe and over in contact with the shield portion of the bottom rest thereby to tension the stock in a direction normal to the bottom of the shoe and to draw the lasting margin thereof over the shoe bottom.

3. A lasting machine having, in combination, an edge gage for engaging the side of a shoe to position it in the machine, a shoe-bottom rest, said shoe-bottom rest being movable to an operative position in which it is positioned on and close to the marginal edge of the bottom of a shoe held against the edge gage, for supporting and positioning the shoe in a heightwise direction during the operation of the machine, and to an inoperative position in which it is withdrawn from the edge of the shoe, and means for moving said bottom rest to each of said positions.

4. A lasting machine having, in combination, an edge gage for engaging the side of a shoe to position it in the machine, a shoe-bottom rest having a shield portion, said shoe-bottom rest being movable to an operative position in which its shield portion is positioned on, and close to the marginal edge of, the bottom of a shoe held against the edge gage and to an inoperative position in which its shield portion is withdrawn from the edge of the shoe, and means for moving said bottom rest to each of said positions.

5. A lasting machine having, in combination, an edge gage for engaging the side of a shoe to position it in the machine, a shoe-bottom rest having a shield portion over which the lasting margin of the stock to be lasted is drawn during the operation of the machine, said shoe-bottom rest being movable to an operative position in which its shield portion is positioned on, and close to the marginal edge of, the bottom of a shoe held against the edge gage and to an inoperative

position in which its shield portion is withdrawn from the edge of the shoe, spring means for moving the bottom rest to said inoperative position, and operator-controlled means for moving the bottom rest to operative position.

6. A lasting machine having, in combination, means for engaging the bottom of a shoe adjacent to the marginal edge thereof, and gripper means for seizing the lasting margin of the stock to be lasted and for pulling said stock in a direction substantially parallel to the bottom of the shoe and over said shoe-bottom engaging means, said gripper means including a front jaw and a rear jaw constructed and arranged first to close on the lasting margin of the stock, then to move together inwardly over the shoe bottom while so closed on the stock, and finally to release the stock by individual movements of both of said jaws away from opposite sides of the lasting margin of said stock.

7. A lasting machine having, in combination, means for engaging the bottom of a shoe adjacent to the marginal edge thereof, and gripper means for seizing the lasting margin of the stock to be lasted and for pulling said stock in a direction substantially parallel to the bottom of the shoe and over the shoe-bottom engaging means, said gripper means comprising a movable rear gripper jaw, means for reciprocating said rear jaw back and forth over the bottom of the shoe, a front jaw associated with said rear jaw and mounted for movement relative thereto, resilient means tending to move said front jaw toward said rear jaw thereby to close the jaws on the lasting margin of the stock to be lasted, and means for so controlling the action of said resilient means that the jaws first yieldingly close on the stock, next move together inwardly over the bottom of the shoe to tension the stock, and then separate to release the stock, said controlling means being so constructed and arranged that the inward movement of the front jaw is continued during the separating movement of said jaw.

8. A lasting machine having, in combination, means for engaging the bottom of a shoe adjacent to the marginal edge thereof, and gripper means for seizing the lasting margin of the stock to be lasted and for pulling said stock in a direction substantially parallel to the bottom of the shoe and over said shoe-bottom engaging means, said gripper means comprising a movable rear gripper jaw, power means for reciprocating said rear gripper jaw back and forth over the bottom of the shoe, a front jaw associated with the rear jaw and mounted for movement relative thereto, spring means for urging the front jaw toward said rear jaw to close said jaws on the lasting margin of the stock to be lasted, cam means for so controlling the action of said spring means that the jaws first yieldingly close on the stock, next move together inwardly over the bottom of the shoe, and then separate to release the stock, said cam means being so constructed and arranged that the inward movement of the front jaw is continued during the separating movement of said jaws, and operator-controlled means for holding the front jaw away from the reciprocating rear jaw.

9. A lasting machine having, in combination, means for engaging the bottom of a shoe adjacent to the marginal edge thereof, said means being movable between operative and inoperative positions, and gripper means for seizing the lasting margin of the stock to be lasted and for

pulling said stock in a direction substantially parallel to the bottom of the shoe and over said shoe-bottom engaging means, said gripper means comprising a movable rear gripper jaw, power means for reciprocating said rear gripper jaw back and forth over the bottom of the shoe, a front jaw associated with the rear jaw and mounted for movement relative thereto, spring means for urging the front jaw toward said rear jaw to close said jaws on the lasting margin of the stock to be lasted, cam means for so controlling the action of said spring means that the jaws first yieldingly close on the stock, next move together inwardly over the bottom of the shoe, and then separate to release the stock, said cam means being so constructed and arranged that the inward movement of the front jaw is continued during the separating movement of said jaws, and means for moving said shoe-bottom engaging means to its inoperative position and for holding the front jaw away from the reciprocating rear jaw.

10. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over the shoe-bottom engaging means thereby to tension the stock heightwise of the shoe and to draw its lasting margin inwardly over the shoe bottom, and means movable toward the bottom of the shoe for pressing the overdrawn lasting margin against the shoe bottom.

11. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over in contact with the shoe-bottom engaging means in different locations successively along the edge of the shoe bottom, and means operating in time relation to the action of said pulling means for pressing the tensioned lasting margin of the stock against the bottom of the shoe in a location closely adjacent to, but spaced lengthwise of the shoe from, the pulling means.

12. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over the shoe-bottom engaging means in different locations successively along the edge of the shoe bottom, and means operating in time relation to the action of said pulling means for pressing the tensioned lasting margin of the stock against the bottom of the shoe in a location closely adjacent to, but spaced lengthwise of the shoe from, the pulling means, said pressing means being movable, while in pressing engagement with the lasting margin of the stock, to feed the shoe.

13. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over the shoe-bottom engaging means thereby to tension the stock heightwise of the shoe and to draw its lasting margin inwardly over the shoe bottom, and means movable toward the bottom of the shoe for pressing the overdrawn lasting margin against

the shoe bottom and in a direction lengthwise of the shoe to feed the shoe.

14. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over the shoe-bottom engaging means thereby to tension the stock heightwise of the shoe and to draw its lasting margin inwardly over the shoe bottom, and a presser foot movable toward the bottom of the shoe to press the overdrawn lasting margin against the shoe bottom, said presser foot being movable in a direction lengthwise of the shoe while in pressing engagement with said lasting margin of the stock to feed the shoe.

15. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over the shoe-bottom engaging means thereby to tension the stock heightwise of the shoe and to draw its lasting margin inwardly over the shoe bottom, and means movable toward the bottom of the shoe for pressing the overdrawn lasting margin against the shoe bottom, said pressing means being also operable to move the shoe away from the shoe-bottom engaging means.

16. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over the shoe-bottom engaging means thereby to tension the stock heightwise of the shoe and to draw its lasting margin inwardly over the shoe bottom, and a presser foot movable toward the bottom of the shoe to press the overdrawn lasting margin against the shoe bottom, said presser foot being movable in a direction lengthwise of the shoe while in pressing engagement with said lasting margin of the stock to feed the shoe, said presser foot being also operable to move the shoe away from the shoe-bottom engaging means.

17. A lasting machine having, in combination, means for tensioning the stock to be lasted and for drawing its lasting margin inwardly over the bottom of a shoe, and means operable in time relation to said tensioning means for pressing the overdrawn lasting margin against the bottom of the shoe, said pressing means comprising a member movable successively toward the shoe bottom and into pressing engagement with the overdrawn lasting margin, in a direction lengthwise of the shoe to feed the shoe, heightwise of the shoe away from the shoe bottom, and in the opposite direction lengthwise of the shoe.

18. A lasting machine having, in combination, means for engaging the bottom of a shoe, means for tensioning the stock to be lasted and for drawing its lasting margin inwardly over the bottom of the shoe, and means operable in time relation to said tensioning means for pressing the overdrawn lasting margin against the bottom of the shoe, said pressing means comprising a member movable successively toward the shoe bottom and into pressing engagement with the overdrawn lasting margin, in a direction lengthwise of the shoe to feed the shoe, heightwise of the shoe away from the shoe bottom, and in the opposite direction lengthwise of the shoe, said pressing

means being also operable, while in pressing engagement with the overdrawn lasting margin, to move the shoe away from the shoe-bottom engaging means.

19. A lasting machine having, in combination, means for engaging the bottom of a shoe, means for tensioning the stock to be lasted and for drawing its lasting margin inwardly over the bottom of the shoe, and means operable in time relation to said tensioning means for pressing the overdrawn lasting margin against the bottom of the shoe, said pressing means comprising a member movable successively toward the shoe bottom and into pressing engagement with the overdrawn lasting margin, in a direction lengthwise of the shoe, heightwise of the shoe away from the shoe bottom, and in the opposite direction lengthwise of the shoe, said pressing means being also operable, while in pressing engagement with the overdrawn lasting margin, to move the shoe away from the shoe-bottom engaging means.

20. A lasting machine having, in combination, means for engaging the bottom of a shoe, means for seizing the lasting margin of the stock to be lasted and for pulling it in a direction substantially parallel to the bottom of the shoe and inwardly from the edge thereof in different locations successively along the edge of the shoe bottom, means operating in time relation to the action of said pulling means for pressing the tensioned margin of the stock against the bottom of the shoe in a location closely adjacent to, but spaced lengthwise of the shoe, from the pulling means, said pressing means, while in pressing engagement with the lasting margin, being movable in a direction lengthwise of the shoe and operable to move the shoe away from the shoe-bottom engaging means.

21. A lasting machine having, in combination, means for engaging the bottom of a shoe adjacent to the marginal edge thereof, means for seizing the lasting margin of the stock to be lasted and for pulling it in a direction substantially parallel to the bottom of the shoe and over the shoe-bottom engaging means in different locations successively along the edge of the shoe bottom, means operating in time relation to the action of said pulling means for pressing the tensioned lasting margin of the stock against the bottom of the shoe in a location closely adjacent to, but spaced lengthwise of the shoe from, the pulling means, said pressing means being movable, while in pressing engagement with the lasting margin, to feed the shoe, and a member for applying additional pressure to the lasting margin while said pressing means is out of engagement with said lasting margin.

22. A lasting machine having, in combination,

means for tensioning the stock to be lasted and for drawing its lasting margin inwardly over the bottom of a shoe, means operable in time relation to said tensioning means for pressing the overdrawn lasting margin against the bottom of the shoe, said pressing means comprising a member movable into and out of pressing engagement with the lasting margin, in a shoe-feeding direction while in pressing engagement with the lasting margin and in the reverse direction while out of pressing engagement with said lasting margin, and a second pressing means movable into engagement with said lasting margin for applying continued pressure thereto and to prevent retrograde movement of the shoe.

23. A lasting machine having, in combination, means for drawing the lasting margin of the stock to be lasted inwardly over the bottom of a shoe, a first pressing means movable successively into pressing engagement with the lasting margin, in a shoe-feeding direction, out of pressing engagement and finally in a feed-return direction, and a second pressing means movable into pressing engagement with the lasting margin to apply continued pressure thereto after the first pressing means has moved out of pressing engagement therewith and to prevent retrograde movement of the shoe.

24. A lasting machine having, in combination, means for drawing the lasting margin of the stock to be lasted inwardly over the bottom of a shoe, a first pressing means movable successively into pressing engagement with the overlasted margin, in a shoe-feeding direction, out of pressing engagement and finally in a feed-return direction, and a second pressing means movable into pressing engagement with the lasting margin to apply continued pressure thereto after the first pressing means has moved out of pressing engagement therewith and to prevent retrograde movement of the shoe, the said pressing means each comprising a narrow blade-like member.

25. A lasting machine having, in combination, means for drawing the lasting margin of the stock to be lasted inwardly over the bottom of a shoe, a first pressing means movable successively into pressing engagement with the overlasted margin, in a feeding direction, out of pressing engagement and finally in a feed-return direction, and a second pressing means movable into pressing engagement with the lasting margin to apply continued pressure thereto after the first pressing means has moved out of pressing engagement therewith and to prevent retrograde movement of the shoe, the said pressing means each comprising a narrow blade-like member provided with a series of sharp teeth for engaging the lasted margin.

JOSEPH FOSSA.
